HOPPER-CARRYING THREE-WHEELED SWAMP BUGGY

Ward T. Commons, Halsey, Oreg.

Filed Oct. 18, 1965, Ser. No. 87,578

Term of patent 14 years

(Cl. D14—3)

Fig. 1.

Fig. 4.

Fig. 5.

*Fig. 2.**Fig. 3.*

FIGURE 1 is a top perspective view of a hopper-carrying three-wheeled swamp buggy showing my new design.
 FIGURE 2 is a side elevational view thereof.

FIGURE 3 is a top plan view thereof.

FIGURE 4 is a front end elevational view thereof.

FIGURE 5 is a rear end elevational view thereof.

I claim:

The ornamental design for a hopper-carrying three-wheeled swamp buggy, substantially as shown.
